LIQUID CONDUCTOR HEATER

Marshall W. Hanks, Madison, Wis.

Application April 16, 1931, Serial No. 530,489

5 Claims. (Cl. 219—40)

This invention relates to liquid conductor heaters of the type in which a liquid conductor within a container is arranged to establish an electrical connection between two electrodes connected in a circuit so that the passage of current between the electrodes through the liquid heats the liquid and causes it to be heated or heated and vaporized. The present invention is an improvement upon the invention of Marshall W. Hanks and George H. Nelson, described and claimed in their copending application Serial No. 530,490, filed April 16, 1931.

The principal object of the invention is to provide an improved liquid conductor heater in which a quantity of liquid, such as a solution of a medical compound, may be vaporized by the passage of an electric current therethrough, so that a medicated vapor is given off which may be inhaled by the user for the treatment of afflictions of the nose or throat. A further important object of the invention is to provide a liquid conductor heater of the type referred to having improved means for permitting the starting and stopping of the apparatus. Still another object of the invention is to provide an improved liquid conductor heater which may be mounted in either of two positions, in one of which the liquid within the vessel of the apparatus establishes an electric circuit between the electrodes, while in the other position the liquid automatically assumes a position out of contact with the electrodes so that the circuit is thereby interrupted. Another object of the invention is to provide a liquid conductor heater of the type referred to having electrodes which are normally immersed in the liquid, but within a tube or chamber of restricted dimensions as compared with the area of the liquid-containing vessel, so that the heating and vaporization of the liquid takes place within a relatively small body of the total liquid contained within the vessel. The apparatus thus has the advantage that the vaporization may be started quickly and without causing a circulation of the heated liquid throughout the entire body of liquid in the vessel. Other objects relate to various features of construction and arrangement which will appear more fully hereinafter.

The nature of the invention will be understood from the following specification taken with the accompanying drawings, in which one embodiment is illustrated. In the drawings,

Fig. 1 shows a vertical longitudinal section through one form of apparatus embodying the present invention;

Fig. 2 shows a horizontal section taken on the line 2—2 of Fig. 1;

Fig. 3 shows a vertical section on the line 3—3 of Fig. 1; and

Fig. 4 is a partial longitudinal sectional view similar to that of Fig. 1, showing the apparatus standing on its end, in order to cause the liquid to pass out of contact with the spaced electrodes.

As illustrated in the drawings, the invention comprises a vessel 10 having a flat bottom wall 10^a adapted to rest upon a table or other support, a parallel top wall 10^b, an end wall 10^c, which extends at right angles to the bottom wall 10^a, and a curved end wall 10^d, the two end walls uniting the side walls 10^e. The vessel 10 may 15 preferably be formed of insulating material and it is adapted to contain a body of liquid 11 which may be a liquid solution of a medical compound adapted to be vaporized for the treatment of nose, throat, or chest diseases or infections, for example, although the vapor resulting from the operation of the apparatus may be used for any other desired purpose. The upper surface 11^a of the liquid 11, when the vessel 10 is resting upon its lower wall 10^a, is preferably somewhat below 25 the top wall 10^b which is provided adjacent the end wall 10^d with an upwardly flaring mouth 10^f.

The electrodes between which the liquid 11 is adapted to establish a connection are preferably mounted in a removable unit 12, comprising a 30 tapered plug 13 having a cylindrical tube 14 extending downwardly therefrom. The plug 13 and the tube 14 may be molded of rubber or other suitable insulating material and they may be formed of the same or different materials, as de- 35 sired. The tube 14 is preferably formed of material having thermal as well as electrical insulating qualities. These members 13 and 14 have a common tubular passage 15 extending upwardly therethrough and preferably outwardly flared 40 and may be enlarged at its upper end as shown at 15^a. Within this passage there are mounted the vertically extending spaced electrodes 16 which form the terminals of an electric circuit. These electrodes extend downwardly to a point 45 adjacent the open lower end of the tube 14 so that the liquid, which seeks its natural level within the tube, corresponding to the level of the liquid within the body of the vessel 10, rises upwardly around the electrodes and establishes an 50 electric circuit between them so that if they are otherwise connected to a source of current supply, a current passes between them through the liquid and causes a portion of the liquid to vaporize with the result that the vapor rises up- 55

wardly through that portion of the passage 15 which lies above the level of the liquid. The tapered plug 13 may directly engage the tapered wall of the mouth 10^f of the vessel, but an annular spacer 17, formed of cork or other suitable insulating material, is preferably interposed between the mouth 10^f and the plug. The tube 14 may be attached to the plug 13 but, if it is not so supported, it may be held in place, for example, by frictional contact with the electrodes.

The electrodes 16, which are preferably in the form of flat bars, have their upper ends bent outwardly as shown at 16^a so that they occupy flat recesses 13^a which extend outwardly in opposite directions in the upper face of the plug 13 on opposite sides of the passage 15. The outer ends of the parts 16^a of the electrodes are reversely bent as shown at 16^b for the purpose of clamping in place and making electrical contact with the extremities 18^a of a pair of electrical conductors 18 which lead from a source of current supply. These conductors, which are insulated, except at their extremities 18^a, occupy grooves 13^b which are formed around the outer portions 25 of the plug 13 and they are then carried downwardly through an opening 13^d at the edge of the plug, as shown in Fig. 3. The outer edge of the upper portion of the plug is threaded and this threaded part is engaged by the correspondingly threaded portion of the down turned flange 20^a which is formed as a part of the cap 20. This cap 20 is formed of insulating material and it has an upwardly tapered passage 21 formed therein to communicate with the passage 15 so that the vapors created by the vaporization of the liquid are discharged from the passage 21 which opens in the center of the upwardly extending annular flange 20^b formed on the cap member. The cap member is provided on its under side with a central annular projection 20^c which engages the upper side of the plug 13 and holds the out-turned arms 16^a of the electrodes firmly in place. The undersurface of the cap 20, surrounding the central portion 20^c, engages the in-turned extremities 16^b of the electrodes and maintains them in firm contact with the extremities 18^a of the electrical conductors leading from the source of current supply.

With the apparatus assembled as above described, and with the electrical conductors 18 connected to a source of electric current, the tube 14 extends downwardly into the liquid 11 as shown in Fig. 1 and the current passes between the electrodes 16, thus vaporizing gradually that portion of liquid which occupies the tube 14 so that a vapor is given off from the mouth of the passage 21. If desired, a vent hole 22 may be provided in the tube 14 above the normal level of the liquid 11 so that if any excessive bubbling of the liquid occurs within the tube due to the boiling thereof, the liquid portion of the bubbles may pass outwardly into the vessel 10 through the opening 22 instead of being carried upwardly by the vapor. As the liquid within the tube 14 is vaporized by the passage of the current, it is replenished from below by the inflow of a portion of the liquid constituting the body of liquid within the vessel 10 and thus the vaporization of the liquid may be continued indefinitely, as long as there is a quantity of liquid remaining in the vessel 10, sufficient to establish a connection between some portion of the two electrodes 16. Due to the fact that the electrodes are enclosed within a thermal insulating tube of relatively small area, the vaporization of the

liquid may be started very rapidly when the circuit is first established and the tube will prevent the heat generated by the passage of the current from being dissipated through the body of the liquid in the vessel. As the opening or 5 openings 22 are relatively small, there is no circulation of the liquid through the tube into the vessel and if the opening or openings 22 are not sufficient to relieve the bubble formation in the upper part of the tube, such relief is furnished 10 by the enlargement 15^a of the passage which prevents the bubbles from passing outwardly through the opening 21 in the cap. When it is desired to discontinue the vaporization of the liquid, the user may merely turn the vessel 10 up on its end, 15 so that it rests upon the end wall 10^c, and this will result in the liquid 11 flowing out of the tube 14, which will then occupy a horizontal position as shown in Fig. 4. The surface of the liquid 11 will then occupy a plane 11^b where it is 20 entirely out of contact with the tube 14 and out of contact with the electrode 16. In this way the circuit between the electrodes may be automatically discontinued when desired merely by the tilting of the vessel from one position to another, due to the fact that the tube 14 is located adjacent one end of the elongated vessel. When the operator wishes to renew the operation of the apparatus, the vessel may be restored to the position shown in Fig. 1 and the circuit will 30 again be automatically established between the electrodes by the liquid rising within the tube 14. In order to prevent the accidental removal of the unit 12 from the vessel 10 when the vessel is being tilted from one position to another, the 35 plugs 13 and spacer 17 may be secured to the flaring mouth 10^f of the vessel.

Although one form of the invention has been shown and described by way of illustration, it will be understood that it may be constructed in 40 various other embodiments within the scope of the appended claims.

I claim:

1. The combination in a liquid conductor heater of a vessel adapted to contain a liquid conductor, 45 said vessel having angularly disposed surfaces on either of which it is self-supporting when placed upon a support, and a pair of spaced electrodes mounted in the wall of said vessel and projecting into said vessel to make contact with the liquid 50 therein when said vessel is resting upon one of said surfaces, said electrodes being out of contact with said liquid when said vessel is resting upon the other of said surfaces.

2. The combination in a liquid conductor 55 heater of an elongated vessel adapted to contain a liquid conductor, an insulating tube extending downwardly into said vessel adjacent one end thereof, a pair of spaced electrodes extending vertically through said tube, said tube being provided with means for admitting liquid from said vessel to the interior thereof for establishing a connection between said electrodes, said vessel having a flat surface at the end thereof removed from said tube whereby the tilting of said vessel 60 onto said flat surface causes said liquid to flow out of contact with said electrodes.

3. The combination in a liquid conductor heater of an elongated vessel having a bottom wall upon which it normally rests, said vessel 70 being adapted to contain a liquid conductor, a tube extending downwardly into said vessel adjacent one end thereof and having its lower end open to permit the access of said liquid to the interior thereof, a pair of spaced electrodes ex- 75

tending downwardly into said tube to a point adjacent the lower end thereof below the normal level of liquid therein, and an electric circuit in which said electrodes are connected, said vessel 5 having a flat surface at the end thereof opposite said tube whereby said vessel may be tilted onto said flat surface to cause said liquid to flow out of contact with said electrodes in said tube.

4. The combination in a liquid conductor 10 heater, of a vessel having a flat horizontal surface upon which it normally rests and another angularly disposed flat surface upon which it may be supported when tilted, an insulating tube extending into said vessel transversely to said flat 15 horizontal surface, said tube having means for admitting liquid from said vessel into the interior thereof and being located at a point removed from said second named flat surface, and a pair of electrodes spaced apart and extending vertically through said tube to be connected by liquid 20 passing into said tube from said vessel when

it is in its normal horizontal position, said tube being constructed to permit the liquid to flow out of contact with said electrodes when said vessel is tilted onto said second-named flat surface.

5. The combination in a liquid conductor heater, of a vessel having a flat horizontal surface upon which it normally rests and another angularly disposed flat surface upon which it is self-supporting when tilted from its normal position, an insulating plug mounted in the wall of said vessel, and a pair of spaced electrodes carried by said plug and extending into said vessel parallel to each other at a point removed from said second named flat surface, whereby 15 said electrodes are connected by the liquid in said vessel when said vessel is resting upon said flat horizontal surface and are out of contact with said liquid when said vessel rests upon said angularly disposed flat surface.

MARSHALL W. HANKS.
